UNITED STATES PATENT OFFICE.

JAMES O. WELTY, OF NEVADA, OHIO.

BOSOM-IRONING BOARD.

SPECIFICATION forming part of Letters Patent No. 284,697, dated September 11, 1883.

Application filed June 13, 1881. (No model.)

To all whom it may concern:

Be it known that I, JAMES O. WELTY, a citizen of the United States, residing in Nevada, county of Wyandot, and State of Ohio, have invented a certain new and useful Bosom-Ironing Board, of which the following is a specification.

My invention relates to improvements in ironing-boards, in which the bosom-board proper is detachably connected with a supporting-frame, between which and the edges of the board the outer edges of the shirt-bosom are held, and are designed to be supported upon the lap of the operator.

The objects of my invention are, first, to provide for adjustably tightening the bosom-board in its supporting-frame to adapt it for holding fabrics of varying thicknesses; second, to afford for the ready and easy attachment and detachment of the board from the frame; third, to provide means for locking the board to the frame after the board is adjusted to its operative position; and, finally, to distribute the strain upon the bosom when stretched and clamped between the board and frame in two or more parallel lines extending the length of the bosom. I attain these objects by devices illustrated in the accompanying drawings, in which—

Figure 1 is a perspective of an ironing-board and supporting-frame embodying my invention, showing the board swung upon the pivot formed by the intersection of its opposite bevels with those of the frame, and in position to be attached to or detached from the frame; Fig. 2, a plan view of the top of the same; Fig. 3, a cross-section on the line $x-x$ of Fig. 2; Fig. 4, a plan view of the bottom of the board, showing the button for locking the same to the frame; Fig. 5, a cross-section on the line $y-y$ of Fig. 2; and Fig. 6, a detail perspective of one of the side bars, showing the shoulders upon the same.

Similar letters of reference indicate the same parts in the several figures of the drawings.

A A represent the side bars, and B B the end bars, of the supporting-frame of the board. These side bars are inwardly beveled toward the center of the frame for about half their length, as shown at $a-a$, and are outwardly beveled the rest of their length, as shown at

$a'-a'$, and are supported on top of the end bars. As shown in Fig. 2, the side bars are slightly converged from their bottom ends; but they may have straight outer edges and converging inner edges, as desired, the main object in either case being to provide for the adjustment of the board between the inner and beveled edges of the frame.

C represents the bosom-board, beveled at $c-c$ and at $c'-c'$, and wedge-shaped to correspond with the inner edges of the frame. The broad end of the bosom-board is provided with shoulders $d-d$, and with an extension, e , corresponding, respectively, with the shoulders and neck-band of the shirt, the shoulders being beveled upon their under side, as shown in Fig. 4, to provide an edge over which the upper part of the bosom may be drawn; but I do not consider it an essential part of my invention to bevel these shoulders. The end bar of the frame adjacent to the neck end of the board is recessed, as shown at f , to prevent the fabric on the back of the shirt from clogging between said neck end and bar; but the same object may be attained by any other suitable means—as, for instance, by recessing the neck end, or by raising the ends of the side bars, with wedges or blocks intermediate them and the end bar.

Referring to dotted lines $g-g$ in Fig. 1 and full lines $g-g$ in Figs. 5 and 6, the intersections of the bevels upon each side of the frame and board are correspondingly curved, and form shoulders connecting the bottom edges of the opposite bevels upon both the board and the frame. These shoulders form a bearing upon which either the board or the frame has a pivotal movement when attaching them together, and by so doing serve to guide them to place for adjustment.

Upon the under side of the board, and about midway its length, is pivoted a button, I , provided with finger-holes $i-i$, and adapted to lock the board to the frame when turned in the position shown in Fig. 4, it being of course understood that the button shall be friction-tight when in that position upon the side bars.

In operation the board is swung to the position as shown in Fig. 1, and removed from the frame, when, after placing it in position in the shirt, it is rested upon the knees of the

operator, and the frame held at an angle and | 5 when the board is shoved forward in the frame swung upon it, care being taken that the bosom is smooth upon the board before wedging or tightening it in the frame, after which the but-ton is turned to hold it in place.

It will be noticed that when pulling the shirt from the under side of the board to smooth the bosom the fabric will be strained or stretched over the upper edge of the board 10 and the under edge of the frame, at one end of the same, or vice versa at the other end, so that there are two parallel lines of strain the length of the fabric, in consequence of which the strain is distributed between these two edges, and the 15 liability of the fabric to be torn correspondingly lessened. Furthermore, by having two parallel edges over which to draw the fabric there is not the same liability of its receding when the force drawing it is relaxed, for the 20 reason that the combined friction of the two edges serves to hold the fabric to a certain extent after being drawn over such edges.

Tightening the board by a movement parallel relative to the plane of the bosom has not 25 the effect of further stretching the bosom, as is the case when the board is operated at a right angle to the plane of the shirt to tighten it in the frame, like those commonly used, and hence the liability of the board itself to injure 30 the bosom of the shirt is lessened.

The button upon the under side of the board serves not only to lock the board to the frame, but to clamp the fabric, after it is drawn over the edge of the frame, between such edge and 35 the bottom, and to hold it stretched upon the board, even should the board become slightly loosened in the frame. Furthermore, the button, by coming between the knees of the operator, prevents the board from sliding longitudinally when passing the iron over it. For 40 the purpose of tightening the board when not wedge-shaped, the bevels are so formed as to sink the under face of the board below the frame. The under edge of the square end of 45 the board is then beveled, as shown at *k*, so that

when the board is shoved forward in the frame the beveled end will, by contact with the end bar, *B*, be shoved upwardly at an angle to the plane of the frame and cause the respective bevels at each end to pinch. 50

What I claim is—

1. The combination, with the frame inwardly beveled at one end and outwardly beveled at its outer end, of a bosom-board correspondingly beveled and adapted to fit in said frame, 55 substantially as and for the purpose described.

2. The combination, with a bosom-board provided with the beveled edges *c c* and *c' c'*, and having the shoulders *g g*, of a supporting-frame having corresponding bevels and shoulders, substantially as and for the purpose set forth. 60

3. The combination, with a bosom-board provided with the beveled edges *c c* and *c' c'*, and having the shoulders *g g*, of a supporting-frame having corresponding bevels and shoulders, said board and frame having a wedge shape, substantially as and for the purpose described. 65

4. The combination, with the frame consisting of the side pieces reversely beveled at different portions of their length, as described, and end pieces attached to the under side of the same, of the bosom-board provided with beveled sides, as set forth, and a button pivoted to the under side of the board and engaging with the frame, substantially as described. 70

5. The combination, with the supporting-frame inwardly beveled at *a a* and outwardly beveled at *a' a'*, of a bosom-board correspondingly beveled and adapted to be secured in said frame, said board being provided with curved shoulders and an extension corresponding, respectively, with the shoulders and neck of a shirt. 80
